UNITED STATES PATENT OFFICE.

MILTON A. CLENNAM, OF SAN FRANCISCO, CALIFORNIA, ASSIGNOR TO CAHILL & HALL ELEVATOR COMPANY, OF SAN FRANCISCO, CALIFORNIA, A CORPORATION OF CALIFORNIA.

ELEVATOR.

SPECIFICATION forming part of Letters Patent No. 708,755, dated September 9, 1902.

Application filed January 26, 1901. Serial No. 44,773. (No model.)

To all whom it may concern:

Be it known that I, MILTON A. CLENNAM, a citizen of the United States, residing in the city and county of San Francisco, State of California, have invented an Improvement in Elevators; and I hereby declare the following to be a full, clear, and exact description of the same.

My invention relates to improvements in elevators for buildings and for like uses.

It consists of a mechanism by which an elevator-cage or like movable device is raised or lowered in a suitable well or guideway, means by which said movable portion may be started 15 from any point at which it may be standing and moved in either direction up or down to any other stated point where it may be desired to have the movable part stop.

It comprises mechanism which may be operated from any floor or station independent 20 of the station at which the cage may be standing and by which mechanism the cage will be started from its position and caused to move either upward or downward, an automatic 25 mechanism by which the cage or movable part will be stopped at any other desired station without further attention.

It also comprises details of construction 30 which will be more fully explained by reference to the accompanying drawings, in which—

Figure 1 is an elevation showing three floors or stations, winding-drum, and portion of the other mechanism. Fig. 2 is a plan view of 35 same, showing floor, direction-switches, motor, brake, and governor. Fig. 3 is a view of the mechanism situated at the top of the elevator, showing push-levers and detent. Fig. 4 is a similar view of the same at right angles 40 with Fig. 3. Fig. 5 is a view of the locking device of the operating mechanism. Fig. 6 is a side view of the direction-switch. Fig. 7 is a diagrammatic view of the direction-switch. Fig. 8 is a vertical section through 45 the so-called "floor-switch" and cut-off. Fig. 9 is a front view of the same. Fig. 10 is a diagrammatic view illustrating the operation of the device shown in Figs. 8 and 9. Fig. 11 is a view illustrating the means for stopping the cage at any floor.

This invention is generally applicable to elevators or hoists of any description where it is desired to send the movable cage or portion to any floor or station of a large number and to start it and determine its direction 55 from the station where it may be standing or from any station other than this one and to determine at the time of starting the distance and direction to which the cage should go and set in operation a mechanism by which it will 60 be automatically stopped at the desired point without further attention from any operator.

I have here illustrated my invention by three floors or stations; but it will be manifest that any greater or less number may be 65 employed by increasing the parts correspondingly.

A, B, and C represent the doors of three different stations or floors of an elevator or hoisting device.

2 is the winding-drum, around which the hoisting-rope is designed to pass and by which the cage or movable part is raised or lowered when the drum is rotated in either direction by the operation of any suitable motor. The 75 present illustration, while designed to represent any equivalent hoist or elevator and any well-known means by which said apparatus may be operated, is here shown as being actuated by an electrically-impelled motor, as 80 at 3. The electrical current for said motor and for operating the floor or direction switches and other parts is derived from any suitable source or generator, and by suitable connections passing through the respective 85 portions and parts operated by said current the various necessary parts are simultaneously set in operation to produce the desired result.

As shown in Fig. 3, each door has fixed 90 upon it a metal plate with a notch, as at 4, and a lever-arm 5 is fulcrumed to a fixed portion in such relation that one end of the lever-arm enters the notch 4 when the door is closed and is movable about the fulcrum-point when 95 the door is opened. The other end of the lever-arm connects with a slide 6, and this slide consists of a guided bar having as many segmental grooves 7 made in its edges as there may be floors or stations, and there will 100

be one of these bars at each of the stations. 8 represents centrally-pivoted levers having handles 9, by which they may be operated. Each of these levers carries a segment 10, which is turnable with the lever, so as to engage with or be disengaged from the segmental groove 7 of the sliding bar 6. Thus when all of the segments 10 stand so that their cut-away portions and straight faces are in line with the segmental grooves the slides 6 may be moved up or down; but when any one of the segments 10 is turned so that it enters and engages the corresponding groove 7 the slide will be locked and prevented from further motion. Thus, as shown in Fig. 3, the uppermost of the levers or thumb-pieces 9 has been pushed to one side, and this has tilted the lever-arm 8, carrying with it the segment 10, which is so turned as to enter and engage the groove 7 of the slide, and thus prevent the slide from vertical movement, while the other levers, arms, and segments remain in such position that unless so locked the slide might be moved. Each of these levers and segments represents one of the floors, and there are as many of them as there are floors or stations. In the present case three are shown. The upper lever 8, representing the third floor, and the connected parts will be hereinafter used in illustrating the operation of the device. This lever has wires or ropes 12 extending downwardly from it and connecting with the similar upper lever at each of the stations below, so that when the operating-lever 9 is pushed so as to turn the lever-arm 8 it at the same time turns the corresponding lever-arm at each of the floors below. In Fig. 1 the ropes 12 are all in the same vertical plane, and therefore cover one another. The movement last described will simultaneously turn each of the segments 10, and thus every one of the slides at each of the floors will be locked, so that no movement from any other floor can be effected while this lock is in effect. This prevents any interference with the operation of the apparatus which may at any time be taking place from any particular floor or station. The same movement of the tilting arm 8, acting upon the wires or connections 12 at each end of the arm, the wire extending upward, as shown in Fig. 3, pulls upon the bent lever 13, which is centrally fulcrumed, as shown at 14, and one arm 15, which is here shown as of non-conducting material, presses down a spring 16 into contact with a metallic plate 17, and as the spring and the plate are parts of an electric circuit such circuit is closed by this contact. By reason of the locking of all the other doors, as previously described, it will be manifest that no other circuit can be closed or actuated while the first-named one is operated. Therefore all control of the cage for the time being remains with the operator at the first-named station. When the arm 15 is brought down to make the contact between 16 and 17, the other arm

18 moves up into contact with the core 19 of an electromagnet E, which acts as a detent-magnet, and as this magnet is energized at 70 the same instant, as will be hereinafter described, this lever-arm 18 acts as a detent and is retained in position as long as the magnet is energized. This insures a continuation of the contact between 16 and 17 until 75 the deenergizing of the magnet releases the arm 18 and allows it to drop either by gravitation or, as here shown, by the action of the spring 20, connected with the wire 12 or other part, so that the parts here referred to will 80 be restored to their normal position when released. When the lever-arm 18 is thus raised, it enters a diagonal slot 21, made in a horizontally-sliding plate 22. This plate is slotted horizontally and movable upon pins 23, 85 passing through the slot into a fixed support. When the lever-arm 18 thus rises, it enters the lower edge of the diagonally-disposed slot 21 and in its upward movement causes the plate 22 to slide transversely, and as it 90 thus slides the lower edges of the plate, which are between the slots 21, are brought into line with all the other lever-arms 18, and they are thus locked and prevented from being raised while the slide is in this position. The operation of opening the door C takes place before any movement of the lever 8 is made, and as long as the door is opened the lever 5 stands in the position shown in dotted lines, in which case the slide 6 will have been 95 moved down, so that its grooves 7 are out of line with the segments 10, and the latter cannot be actuated as long as the door remains open by reason of the locking of the segments. Whenever the door is closed, the 100 lever-arm 5 is restored to its normal position, and then the slide will be in such position that the lever-arm 8 can be tilted, as previously described. This acts as a lock to the slide and to all the other slides connected therewith, so that no movement of any of the doors can be effected.

The tension of the wires 12 is properly maintained by turnbuckles or equivalent take-up devices located at suitable points in 115 the length of the wires. When the electrical circuit is completed by the contact of the plate 16 and plate 17, an electrical circuit is established through the floor-switch, (shown at F in Figs. 1 and 2,) through the direction-switch, 120 (shown in Figs. 1 and 2,) through the detent E to the brake, thence to the service-switch, and from there back to the contact-plate 17. The energizing of the direction-switch closes the motor-circuit. The direction-switch D is operated, say, by the two coils D' and U' and determines whether the cage is to go up or down, and it consists of a series of copper pins x to x^5 , inclusive, and y to y^5 . The pins are surrounded by spring-barrels, the latter 130 being screwed into a fixed fiber block 26. Below are two swinging fiber blocks 26^a, which have on their upper faces the carbon strips c' and c^2 c^3 . The springs 60 press

upon the pins and insure a simultaneous contact with the strips and the breaking thereof. The strips c' and c^2 and c^3 , &c., are respectively carried upon lever-arms, as 5 27, Fig. 6, fulcrumed at 28 and connected intermediate between the fulcrum and the fiber blocks with the core 29 of the solenoid 30. When one of these solenoids is energized, the 10 attraction raises the fiber block 26³, carried by the arm 27, and this makes contact with the pins in 26, and thus completes the circuit for either up or down movement. If the contact is made for the up movement, the one for the down movement remains open. 15 The series x are connected to y , x' to y' , x^4 to y^4 , x^5 to y^5 . x^2 and x^3 are cross-connected with y^2 and y^3 . The contact being thus made, the current will pass as follows: from the service-switch through wire a , pin y , wire a' , pin 20 x ; carbon c , pin x^2 , wire a^2 , thence in the direction of the arrow m through the motor-armature to wire a^3 and through the rheostat R , pin x^3 , carbon c' , pin x^4 , wire a^4 to service, thus completing the circuit. The field-circuit 25 branches off at x' , passing through wire s , s' , thence through field f , wire s^2 , s^3 , pin x^4 , carbon c' to x^5 , there uniting again with the armature-circuit. If the carbons c , c' are dropped so as to open the up side of the direction-switch and the carbons c^2 , c^3 are raised so as to close the down side, the circuit is made 30 as follows: through wire a , pin y , carbon c^2 , pin y^2 , wire a^5 , pin x^5 , wire a^3 , and through the motor in the direction of the arrow m' , thence through wire a^2 , pin x^2 , wire a^6 , pin y^3 , carbon c^3 , wire a^7 , pin x^3 , wire a^4 . The field-circuit branches at y' , traversing the wire s^4 , s' , field in the same direction as previously described, thence through wire s^2 , s^5 , pin y^4 , carbon c^3 , and uniting with the armature-circuit. The double break of the field-magnet circuit and the quadruple break of the armature-circuit are effected as follows: When, for instance, the first button is turned, plates 17 45 and 16 are contacting, which connects the plate 17 and its wire 59 with the wire 41' through the spring 16. This closes a circuit whose current will pass over wire 41', the plate 33' of the floor-switch, thence to 39, 50 through the arm 36, through the plate 33^D, thence over wire 42^D, through solenoid D', (energizing the same and attracting the switch-plate "Down.") From this point the current passes over wire 56 to the detent E and from 55 thence over wire 57 through brake-magnet 25, over wire 58, switch S, wire a and 59, to plate 17. This completes the closing of the direction-switch circuit. As soon as the cage has arrived at its destined station the arm 37 will 60 drop into the notch, and consequently the connection between 33' and 33^D will be broken. This will cause the circuit to open over 42^D to the solenoid D', deenergizing the same, allowing the plate marked "Down" to drop and 65 break the field-magnet circuit at y' , y^4 and the armature-circuit at y , y^2 , y^3 , and y^5 , thus producing a double break of the field-magnet circuit.

cuit and a quadruple break of the armature-circuit. The cutting off of the circuit over the wire 56 will deenergize the detent E, thus 70 breaking the connection between plates 16' and 17 by releasing the arm 18, breaking the circuit over wire 41' to plate 33', which completes the breaking of the circuit to operate the direction-switch. The discontinuance of 75 the current over wire 57, leading from detent E', puts the brake in operation again and puts the wires 58, a , and 59 out of operation. The floor at which the cage is to stop is determined by the floor-switch, the position of 80 which is shown at F in Fig. 2. This switch is shown in detail in Figs. 8 and 9. It consists of a non-conducting annulus or wheel 31, secured to a fixed box or support, as at 32, and having annular conducting rims 33' and 33^D, 85 extending around it and separated from each other, as plainly shown in Fig. 8. 34, 35, and 36 are non-conducting extensions of arms 37, which are pivoted or fulcrumed, as at 38. The outer ends of the arms 37 90 carry the elastic metallic contact-pieces 39 and 40, and these are brought into contact with the rims by the tilting of the arms about their fulcrum-shaft 38. When this contact is made, the current passing through the wire 95 41' and rim 33'', contact-piece 39 and 40, and the intermediate metal shaft, rim 33^D, and wire 42^D, completes this circuit. The current to complete the circuit for either of the arms 34, 35, or 36, two of which are always 100 in contact with the rims, will be derived from the closing of the circuit 16 17, previously described, which determines the floor to which the cage is to go. Thus the circuit 16 17 for floor No. 3 having been closed, the electrical 105 current passes through that and through the corresponding wires 41'', plate 33'', spring connection 39, shaft-spring 40, plate 33^D, and wire 42^D, which leads to the solenoid to operate the direction-switch and through it the 110 motor. From the motor 3 motion is transmitted to turn the drum 2, and the direction of motion having been determined by the direction-switch, previously described, the rotation of 115 this shaft transmits motion through the pinion 43 and gear-wheel 44, as shown in Fig. 1, to revolve the shaft 45, which passes through the box or support 32, as shown plainly in Fig. 8. This shaft has keyed upon its outer end a disk 46, so that the disk is turnable with the 120 shaft 45. The proportion of the pinion 43 to the gear 44 is such that the shaft 45 and disk 46 will be slowly rotated in one direction while the cage is moving one way and rotated in the opposite direction when it is moving 125 the opposite way. The oscillation of the disk 46 in one direction is equal to the full travel of the cage from bottom to top of elevator-shaft and corresponds in the opposite direction with its travel from top to bottom. The 130 object of this is to cut off the current which passes through the wires when the particular floor has been reached, and this is effected by the inner end of the arm 37 dropping into

a depression 47, which is made in a disk 48, loosely turnable upon the shaft 45 and interior of the disk 46. The disk 46 has a radial V-shaped notch 49 made in it and extending from the rim toward the center, as shown in Fig. 9. The loose disk 48 has a projection or spur 50, which projects from it into the notch 49, but having a less width in the direction of rotation than that of the notch, the disk 48 is capable of a small movement independent of the disk 46 for a purpose to be herein-after described. The current passing through the wires, as previously described, and the arm 34 being turned about its pivot-point by reason of the roller 51 on the inner end of the arm 37 resting upon the periphery of the disk 46, the arms 34 37 will stand at an angle, as shown in Fig. 9, and the elastic contacts 39 40 will rest upon the rims, thus completing the circuit, which passes thence through the direction-switch and the motor, and the motor being thus energized sets the winding-drum in motion and starts the cage. The disk 46 travels beneath the roller 51 until the latter arrives at the notch 49, and the roller will then be transferred and supported upon the periphery of the disk 48 until it reaches the point where it can drop into the groove 47 of the rim 48. The disk 48 is of slightly-smaller diameter than the disk 46 for the purpose of preventing frictional contact with 48, which would otherwise be caused by the other arms 37 resting on the disk 46 and which would impede the independent movement of disk 48. The object of the independent disk 48 is to cause a quick sudden cut off, so that the cage will be stopped at the moment it reaches the desired floor, and this is effected by the lug 50 on the disk 48. To demonstrate this, referring to Fig. 9 and assuming that the arms 37 34 on the left side are to be operated upon, the arm in the center has just been straightened and the right side wall of the notch 49 has caught up with the lug 50 is pushing 48 along in the direction of the arrow. In its further travel the left-hand wall of notch 49 will first reach the roller on 34 37, and the roller will be transferred upon the disk 48 and keep on riding on the same until notch 47 arrives at the roller. The moment the roller comes in touch with the notch 47 its spring 52 will force the roller down into the notch, and that will cause a pull upon disk 48 toward the radial line of the arm to which the former can yield, having that play from the notch 50 to the left-hand wall of notch 49. This yielding will allow the spring 52 on arms 34 37 to straighten it at once and cause a sudden cut off. On the other hand, if there was simply a notch in the disk 46 the arm would gradually drop into the notch as the disk moves slowly and commence to cut off before it had reached the bottom of slot 47, which would stop the whole mechanism before the cage had reached its destined floor. The operation of the device as here illus-

trated, with the starting-levers 9 set for the third floor, would then be that the contacts 33", 39, and 40 of the arm 34 would conduct the current of the wires 41" 42", and the direction-switch D having been simultaneously set by the current, as previously described, the disk 46 would be slowly revolved in the direction which would bring the notch 47 in line with the roller 51 of the arm 34, and when the notch has reached that roller the roller would drop into it, and the spring 52, throwing the arm immediately into an approximately radial position, will break the contacts 33" 39 40, thus cutting off the current and stopping the whole apparatus. Whenever the cage is caused to move in the other direction, the energizing of some other circuit through the contact of another of the arms 37 will cause the corresponding reversal of direction of movement of the disk 46, and as it starts the arm, which, as shown at 35, is in a radial position, will be turned about its pivot, overcoming the tension of the spring 52 as the roller 51 is caused to move out of the notch 47 and upon the rim 48. It does not matter how many contacts are made with the rims 33, the action will only take place through the particular arm 37, &c., through which the current is directed by the setting of the apparatus in the first instance for the floor-switch.

The operation of the elevator will be as follows: Assuming that the cage is at the bottom and is to be sent to the third floor, the corresponding lever or button is turned which connects the plate 17 with wire 41", the latter leading to contact-plate 33" on floor-switch, and through contact-springs 39 40 to contact marked 33", through wire 42", through solenoid U', (causing the latter to close at the direction-switch 26^a up,) from there through wire 56 to detent E, causing the arm 18 to be attracted and held up during the travel, from detent E through wire 57 to the brake 25, releasing the same, thence through wire 58 to service-switch S, through wire a and 59 back to plate 17, which completes the circuit. By the closing of the direction-switch U² the motor-current is established, as previously described and shown in the diagrammatic view Fig. 7. The motor-wire a³ is connected with a cut-off at 60, Fig. 2. This cut-off consists of a segment G, Fig. 9, having a contact-plate g, which connects the two ends of wire a³, thus keeping the circuit always closed. This segment is hung from the pin g' upon a support 61, Fig. 8, which also carries the binding-posts 62 of the wire a³. Projecting from the top of the segment is a short arm g², which is to come in contact with either of the pins 63 upon the side of the disk 46. This takes places when either of the arms 34, 35, or 36 should fail to break contact and cause the disk to travel still farther until a pin 63, striking the arm g², would tilt the segment and break the cir-

cuit in the wire a^3 . This breaks the motor-circuit, and consequently stops the travel of the cage.

In the diagrammatic view Fig. 10 I have illustrated the working of the floor-switch more clearly. The cage is supposed to be at floor 3, and it is desired to send it to the first floor. As previously shown, the connection at 33" has been broken by the arrival 10 of the cage and has left the springs of 35 to connect 33" with "down" strip 33^p and also 33' with the down strip. The first-floor button or lever being turned, this establishes the circuit from the detent E to 33', to "Down," 15 to solenoid D', by wire 42^p, operating the motor for down movement, and thence to detent E, as previously described. The disk 46 commences to move now in the direction of the arrow, connecting 33" and "up" strip again. 20 On reaching 33" the contact is broken; but there being no current here (as only 33' is connected) the disk will still travel on laying arm 35, so as to connect 33" with up strip, thus getting same ready for the up trip, until 25 reaching 33', when the arm 36 will be straightened, current broken, and the cage will stop at its destination.

In Fig. 11 is illustrated more clearly the manner in which the cage is always brought 30 to the floor-line. Suppose the disk 46 is traveling in the line of the arrow, taking disk 48 along by its lug 50, and an arm 37 is already traveling on the disk 48. Now as soon as the 35 edge of the notch 47 presents itself to the roller the roller will quickly take hold of it and by the impulse of its spring 52 pull it toward itself to line r^q , where the arm will then be in a radial line and the contact broken, this line being the floor-line. As before 40 stated, the loose mounting of disk 48 and the play of lug 50 in notch 49 allow this independent movement. It can be seen from this illustration that the roller travels a little beyond the line r^q , thus keeping the contact 45 closed a little longer and allowing the disk 46 and with it the cage to travel on until they come to the floor-line as close as possible.

The plates 4 on the doors have notches made in them, and the part above the notch projects farther than the part below, so that when the door is drawn down and closed this extension will engage the end of the lever 5 and insure its movement and action upon the slide 6. The doors are of the type of vertically-sliding doors, and when the door is raised either to put in or take out a load the lever 5 is pushed out of the notch 4 and the slide 6 takes the position shown in dotted lines, Fig. 3—that is, being out of line with 55 the segments 10, which now prevent any turning of the handles while the door is open. Then when the door is closed any lever can be operated, as the segments coincide again with segments 10. When the door is 60 down or closed, the lever 5 rests in the notch 4 of the door and the slide is in the position as shown in full lines in Fig. 3—that is, coinc-

iding with the segments 10—thus allowing the handles 9 to be operated. When the door is closed, then the slide is in its normal position, and when the motor is at rest the spring 20 will pull back the respective lever 8 to its normal position again, but will not affect the slide 6, as the latter is only operated by the movement of the door. While the door remains open no lever 9 can be moved, and when the door has been closed and one of the levers 9 has been turned to lock the slide the movement of the lever-arm 18 by the wire 12, connecting it with the arm 8, moves the slide 80 22 and prevents the movement of any other lever 9 and its connections. The effect of turning the segment 10 is to lock the doors, so that they cannot be opened while the cage is in motion. The arrangement of the contact-plates c^c and a number of pins through which the circuits are completed allows the field and armature circuits to be broken at such a number of points simultaneously as to reduce the spark produced by the break, so 85 that it is not objectionably noticeable.

Having thus described my invention, what I claim as new, and desire to secure by Letters Patent, is—

1. The combination in an elevator of stations or floors; a cage suspended and movable between said floors; a motor and mechanism by which the cage is operated; independently-operated mechanism including controlling switches, circuit-closing devices for each floor and connected together in sets and detents for the circuit-closing devices; and electric circuits and mechanism energized thereby to determine the direction and distance of movement of the cage. 95

2. The combination in an elevator of stations or floors; a cage suspended and movable between said floors, a motor and mechanism by which said cage is raised and lowered, and mechanisms comprising direction and floor switches, manually-operated circuit-closing devices and detents therefor, said circuit-closers for each floor being connected together in sets so that the mechanism for either floor may be operated from any of the floors, and 115 electric circuits and mechanism energized thereby to determine the direction and distance of movement of the cage. 105

3. The combination in an elevator of stations or floors; a cage suspended and movable between said floors, a motor and mechanism by which said cage is raised and lowered, levers connected in sets to be operated in unison from either floor, independent electrical contacts each adapted to be closed or opened by the operation of one of said sets of levers, circuits controlled thereby and mechanism operated by the closing and opening of said circuits whereby the direction of movement of the cage is determined and effected. 120 125 130

4. The combination in an elevator of stations or floors; a cage suspended and movable between said floors, a motor and mechanism by which said cage is raised and lowered, le-

- vers connected in sets to be operated in unison from either floor, independent electrical contacts each adapted to be closed or opened by the operation of one of said series of levers, and an electromagnet energized by the closing of said circuit, an armature and lever actuated by said electromagnet whereby the first-named circuit remains closed until the electromagnet is deenergized.
5. An elevator-cage, a motor and mechanism by which said cage is raised or lowered, levers connected in sets, one of which is located at each floor or station and capable of being operated in unison from either floor, independent electrical circuits each adapted to be closed or opened by the operation of one of said series of levers, an electromagnet and movable armature controlling the circuit closer, a locking device consisting of a movable slide having diagonal slots into which the armature is moved by the closing of the circuit which it controls, and the movement of any other armature and closing of its circuit are prevented.
10. An elevator-cage, a motor and mechanism by which said cage is raised or lowered, levers located at each floor and connected in sets of one for each floor, electrical circuit-closing devices operated in unison with the movement of either series of levers, and locking devices operated by the movement of either of the series of levers whereby the movement of one series of levers, prevents the operation of all the other series.
15. An elevator-cage, a motor and mechanism by which the cage is moved up or down, a series of slides corresponding with the number of floors and having segmental grooves in the edges, fulcrumed levers connecting with the slides and operated by the opening and closing of the doors, levers connected in sets for each floor and electrical circuits, each opened or closed by the operation of one of said series of levers, segments turnable in unison with the levers and adapted to engage the grooves and the slides whereby the movement of one lever locks and prevents movement of all the doors.
20. An elevator-cage, a motor and mechanism by which the cage is moved up or down, electrical circuits and mechanism including sets of levers located at each floor and connected together by which either circuit is closable from any of a number of floors or stations, a direction-switch actuated by the closing of such circuits whereby the movement of the cage up or down is determined.
25. An elevator-cage, a motor, a mechanism by which it is moved up or down, electrical circuits and mechanism including sets of levers located at each floor and connected together by which either circuit is closable from any of a number of floors or stations, a direction-switch actuated by the closing of such circuits whereby the movement of the cage up or down is determined, said switch consisting of insulated pins, and wires connect-
- ing said pins, so that electrical currents may be transmitted to the motor in reverse directions, contact-plates and a solenoid by which said plates are moved into contact with the pins when the solenoid is energized.
30. An elevator-cage, a motor, mechanism by which it is moved up or down, sets of levers at each floor connected together in sets so that either set can be operated from any floor, a direction-switch consisting of pins, connecting-wires therefor whereby currents in reverse directions may be transmitted to a motor, solenoids with movable cores, fulcrumed lever-arms connected with and movable by said cores when the solenoids are energized, and insulated contact-plates carried by the levers and capable of connecting either set of pins to give direction to the motor and the cage.
35. An elevator-cage, a motor, mechanism by which the cage is raised or lowered, levers connected in sets, either set of which may be operated from any floor, electrical circuits controlled by the movements of said levers, a direction-switch and an electrical circuit whereby the direction of motion of the cage is determined and a floor-switch and electrical controlling-circuit whereby the floor at which the cage should stop is determined.
40. An elevator-cage, a motor or mechanism by which it is raised or lowered, levers connected in sets, either set capable of being operated from either floor, independent electrical circuits, either of which is closed by the operation of one of the sets of levers, a floor-switch and electrical circuits controlled by the levers whereby the operation of any set of levers belonging to a floor sets the floor-switch to stop the cage at the desired floor or station.
45. The combination with a vertically-movable elevator of levers connected in sets and operated from either floor or station, independent electrical circuits closed by the operation of either set of levers, a motor and direction-switch actuated by the closing of said circuit to determine the direction of motion of the elevator, a floor-switch consisting of circular metallic insulated rings, fulcrumed levers carrying corresponding contacts, a disk revoluble in unison with the movements of the motor and elevator-cage, said disk having a notch in its periphery into which the contact-carrying lever drops, and breaks the electrical circuit when the cage has arrived at the desired floor.
50. A floor or station switch for vertically-movable elevator-cages consisting of stationary, insulated metallic rings, spring-pressed lever-arms fulcrumed at intervals and corresponding in number with the floors or stations, a disk mounted upon a shaft concentric with the rings, and intermediate mechanism whereby it is turnable in unison with the movements of the motor and cage and in either direction, said disk being mounted in line with the inner ends of the lever-arms which travel upon the

periphery of the disk, contacts carried by the outer ends of said arms and caused to press upon the peripheries of the rings, conducting-wires connecting the said rings to which electrical circuits are completed by said contact, a notch formed in the periphery of the revolvable disk into which the inner end of either arm drops to break the contact between its outer end and the rings when the notch arrives in line with said arm and the cage at the corresponding floor or station.

15. A vertically-movable elevator-cage, a motor and mechanism by which said cage is moved in either direction, a switch by which the floor or station at which the cage is to stop is determined, said switch consisting of stationary insulated conducting-rings, each having one wire of an electrical circuit connected therewith, lever-arms corresponding with the number of stations fulcrumed with relation to said rings having contact-pieces upon the outer ends, a revolvable disk mounted upon the shaft concentric with the rings and turnable in unison with the movements of the motor and cage, rollers upon the inner ends of the lever-arms adapted to rest upon the periphery of the disk whereby the contacts at the outer ends are pressed against the rings to complete the circuits, controlling devices at each floor or station whereby an electrical circuit is completed through the arm corresponding with the station at which the cage is to stop, a notch formed in the periphery of the movable disk, a spring acting upon the lever whereby the inner end of the lever drops into the notch when the latter arrives in line with the lever whereby the contact between the outer end of the lever and the rings is broken and the cage-actuated mechanism is stopped.

40. 16. The combination in a floor or station switch of an elevator-cage, of stationary insulated conducting-rings having the two wires of an electrical motor-actuating circuit connected therewith, lever-arms fulcrumed at intervals with relation to the rings corresponding with the stations, and carrying upon the outer ends contact-pieces, a disk, a shaft upon which it is mounted concentric with the rings and revolvable in unison with the movement of the motor and cage, rollers upon the inner ends of the lever-arms resting upon the periphery of said disk whereby the contacts of the outer ends are maintained, a notch in the periphery of said disk which passes beneath the inner ends of the arms, a supplemental disk contiguous to the movable one having a notch made in its periphery, and a lug entering the notch of the movable disk having a less diameter than that of the first notch whereby the inner ends of the arms drop into the notch of the loose disk, and an independent movement of the two disks is permitted whereby the cage is caused to stop at approximately the floor-level when moving in either direction.

65. 17. An elevator-cage, a motor and mechanism by which the cage is movable, an elec-

trically-actuated mechanism including controlling-switches and circuit-closing devices, said devices being arranged in sets at each floor by which the direction of movement of the cage is determined, and a detent by which said mechanism is maintained in operation until the cage has reached its destination.

18. An elevator-cage, a motor and mechanism by which the cage is movable, an electrically-actuated mechanism including controlling-switches and circuit-closing devices, said devices being arranged in sets at each floor by which the direction of movement of the cage is determined, an electrically-actuated detent by which said mechanism is maintained in operation, and a circuit closing and opening device actuated in unison with the movements of the cage.

85 19. An elevator-cage, a motor and mechanism by which the cage is movable, an electrically-actuated mechanism including controlling-switches and circuit-closing devices, said devices being arranged in sets at each floor by which the direction of movement is determined, a second mechanism with connections by which it is driven in unison with the movements of the cage, and an electric motor-actuating circuit controlled by said second mechanism to determine the distance to which the cage moves.

20. An elevator-cage, a motor and mechanism intermediate of the motor and the cage, a series of independent electrical circuits and connected mechanism including sets of levers located at each floor and connected together whereby the direction and destination of the cage are determined, an electrical motor-driving circuit, and means for closing said circuit to start the cage in its predetermined direction, in combination with a mechanism and connections by which it is driven in unison with the motor and cage, said mechanism acting to automatically open the motor-circuit when the cage has reached its destination.

21. The combination with an elevator-cage and an electrically-driven motor therefor, of a rotary notched disk driven in unison with the motor and cage, lever-arms by which the electrical circuit of the motor is kept closed by the arms resting upon the rim of the disk, and springs by which any arm arriving at the notch in the disk is moved to break the contact controlled by it, and open the corresponding motor-circuit.

22. The combination with an electrically-driven elevator-motor of a disk turnable in unison with the motor, spring-pressed levers resting upon the periphery of the disk while closing the motor-circuit, a notch in the disk into which the levers fall when passing whereby the circuit is opened and the motor stopped.

23. The combination with an electrically-driven elevator-motor, of a disk turnable in unison with the motor, spring-pressed lever-arms, each controlling an electrical circuit through the motor, electrical contacts which

- are closed when the levers rest upon the periphery of the disk, a notch in said disk into which the levers drop upon reaching it, to open their electrical circuits, and a concentric loosely-turnable and correspondingly-notched disk of slightly smaller diameter, having a lug to engage the main disk, and limit the independent movement of the second disk.
24. The combination with an electrically-driven elevator-motor of two concentric disks, one turnable in unison with the motor and having a wide notch in its periphery, and the other turnable loosely and having a lug projecting to engage the first-named disk and permit a small independent movement, spring-pressed lever-arms fulcrumed with one end resting upon the first disk, and the other acting to close a motor-circuit, and a notch in the loose disk into which the lever-arms are forced by their springs to open their controlled circuits and by which a sudden independent movement of the second disk is effected.
25. The combination in an electric-motor circuit-breaking device, of a disk revoluble in unison with the motor and having a radial notch in its periphery, a second concentrically-mounted, loose disk of smaller diameter having a narrower notch in its periphery and a lug projecting into the notch of the first disk and allowing a small independent movement, contacts through which the motor-circuit passes, spring-pressed fulcrumed levers beneath one end of which the disks revolve, to cause the opposite ends to close the motor-circuits, each lever falling into the notches of the disks when they register and opening its circuit.
26. The combination in an electric-motor circuit-breaking device of concentrically-revoluble notched disks, and spring-pressed fulcrumed levers with one end resting upon the periphery of the disks so as to fall into the notches when they register, electrical motor-circuits and means carried by the outer ends of the levers to close said circuits while the levers rest upon the disks, and to open the circuits when the levers fall into the notches, and an independent circuit-closing plate, and pins carried by the disk and acting to move the plate and open the circuit if the levers fail to act.
27. The combination with an elevator and an electrically-driven motor therefor, of electrical circuits and mechanism including controlling-switches and circuit-closing devices, said devices being arranged in sets at each floor by which the direction of movement of the cage is controlled, a motor-circuit and means by which it is closed to energize the motor in unison with the directing device, and a mechanism driven in unison with the motor and acting to automatically open the motor-circuit and stop the elevator-cage at any station.
28. The combination with an elevator and an electrically-driven motor therefor, of electrical circuits and mechanism including controlling-switches and circuit-closing devices, said devices being arranged in sets at each floor by which the direction of movement of the cage is controlled, means including a disk and lever-arms contacting with the same by which the motor-circuit is closed, in unison with the direction device, a mechanism by which the motor-circuit is automatically opened when the cage reaches the desired station, electrical circuits by which the previously-described circuits are closed, and means connecting each floor or station with the last-named circuits whereby either one may be closed and the cage set in motion and its direction and its terminal station fixed.
29. The combination with an elevator-cage, an electric motor, and intermediate mechanism, and electrical circuits closable to energize the motor, of a direction-switch consisting of double set of contact-plates carried by a single arm, and pins so connected thereby as to produce a double break of field-circuit and quadruple breaks of the armature-circuit.
30. The combination with an elevator-cage and motor, and floors or stations between which the cage is movable, of mechanism by which the motor-circuit is energized and controlling devices at each floor, slides movable to lock or unlock said devices, levers having one end connected with a slide, and a notched plate fixed to and movable with the slideable door, and engaging the opposite end of a lever, whereby the slides are moved in unison with the movements of the doors.
31. The combination with an electrically-operated elevator, devices located at each floor whereby the controlling-circuits are energized, locking-slides and fulcrumed levers connected therewith, of slideable doors with notched plates fixed thereto and engaging the levers, said plates having the upper part projecting over the notches to insure the engagement of the levers during the closing movement of the doors.
- In witness whereof I have hereunto set my hand:
- MILTON A. CLENNAM.
- Witnesses:
- S. H. NOURSE,
JESSIE C. BRODIE.
